UNITED STATES PATENT OFFICE.

THEOPHILUS TUCKER, OF OAKLAND, CALIFORNIA.

METHOD OF ORNAMENTING WALLS OR CEILINGS.

SPECIFICATION forming part of Letters Patent No. 465,102, dated December 15, 1891.

Application filed April 25, 1890. Serial No. 349,536. (No model.)

To all whom it may concern:

Be it known that I, THEOPHILUS TUCKER, a citizen of the United States, residing in the city of Oakland and State of California, have invented a new and useful Improvement in Methods of Ornamenting Walls or Ceilings, of which the following is a specification, reference being had to the accompanying drawings and the letters referring thereto.

Figure 1 is an elevation showing a broken portion of the interior of a room; Fig. 2, a broken view of a wall or ceiling enlarged to give a clear idea of the detail. Fig. 3 is a short piece of wood or a block showing perspective. It is designed as a ground and is removed from the depression or groove to the right of the same. Its use will be more fully explained. Fig. 4 is a plan or elevation for a wall, ceiling, or other interior of rooms, and is designed to show different varieties of the work common to the finish of rooms in panels or other figures. Fig. 5 is designed to show the use of grounds as applied to my mode of work or finish.

The following is the construction, arrangement, and operation of my improved pebble-dash surface for the interior of buildings with varied finish, explaining the mode of preparing and putting on my work.

In the production of the several surfaces various degrees of roughness or combination of depressed, roughened, or pebbled surfaces are obtained by the different methods of manipulation of the plastic material, ornamental depressions being obtained by aid of models of the required outline or figure. In all cases I first apply upon the lath an ordinary scratch-coat of plaster or hair mortar prepared and applied in the usual way, except that I sometimes add to the plaster a portion of good cement, such as "Portland cement" or its equivalent.

One class of work—viz., "graded pebble-surface"—is produced by first applying a common "scratch-coat," as above referred to, and while yet plastic I put on a second hair-mortar coat containing one-fourth part of cement (this amount may, however, be varied) to produce solidity of surface and assist in the retention of the gravel. When required, I smooth the surface with a darby or straight-edge in the usual way. Having selected the

required grades of gravel by screening it, I mix about one quart of cement to each bucket of gravel, wet the compound, and dash it upon and into the yet plastic surface, formed as above described, until the desired effect is produced. The grouping and cohesion of the pebbles on the surface are in part determined by the grade of pebbles employed, and the amount of cement and water mixed therewith. When the various pebble-grouped surfaces are sufficiently dry, the pebbles are more perfectly held in place by administering to the surface a coat of suitable adhesive paint.

Concaved spottings are produced by throwing upon the plastic surface a suitable portion of well mixed cement and hair mortar from the point of a trowel or other suitable instrument, and the operation is continued until by the impact of the material the desired concave effects are produced. These spottings may be varied by throwing in and about such figures different grades of wet or dry gravel and cement. The form and outline of these spottings are also determined by the density or by the plasticity of the compost of cement and hair mortar and are largely obtained by the amount of fluid combined with the materials mentioned.

When small concaves or sinkages are required, I hurl a sufficient portion of coarse gravel and cement or mortar forcibly into the plastic surface, which causes the edges of said sinkages to rise and curve in a peculiar form, as shown in the drawings. Where raised gravel groupings are required of a varied degree of size and texture, they are produced by mixing the gravel with a suitable portion of cement hair mortar, which causes it to cohere more perfectly. The operator then lifts the required kind and amount of gravel so mixed upon the point of a trowel and throws it upon the plastic surface with sufficient force to cause it to adhere and build up by repeated operations with the different grades of gravel until the required grouping or design is completed. Thus any variety of groupings may be formed to produce a variety of designs and unique forms. When a sunk gravel grouping is required, the same operation is performed, except that the gravel is hurled into the plastic surface with sufficient force to form a concave or

sunken figure with raised edges or lips, the pebbles remaining grouped or scattered in and around the concave, as required. This grouping is varied with fine effect when 5 coarse gravel is used by throwing in a finer grade of gravel in and about the same. After the large gravel is placed, unique effects are produced by dabbing the surface with a sponge or similar instrument. Also, the plastic surface of the second or cement hair-mortar coat may be manipulated, roughened, or 10 dabbed with a sponge or other suitable instrument to obtain a unique and roughened surface, which may be decorated separately or be used in conjunction with or to form the 15 background for any desired surface herein described.

When geometrical or conventional sunk-figure work is required for artistic effects, 20 well-oiled wooden stencils, patterns, or models of the desired thickness and kind are sunk into the plastic surface of the second or cement hair coat. Such surface is then roughened or manipulated with a sponge, and when 25 required the surface is treated in gravel, as above described. The stencils or models are removed when the work is sufficiently hardened or set.

When geometrical or conventional ornamentation of a raised character is required, 30 then paper or other pliable stencils are laid on the plastic surface of the cement hair mortar, and the cement and gravel, when mixed to the desired consistency, are thrown into the 35 interstices of the stencil until the required raised figure is obtained.

Irregular and interlacing gravel effects are produced by mixing sufficient cement and gravel with water to the right consistency 40 and by building or throwing the preparation from the point of the trowel upon the plastic surface until the required outline and interlacing effect is produced.

When the above-described surfaces are to 45 be more uniformly pebble-graded or roughened, then dry gravel is mixed with dry cement, which, when hurled or thrown into or between the interstices of the coarser grav-

eled surfaces, scatters more uniformly and gives to the general surface and grouping a 50 naturally roughened effect, which permits better artistic treatment in the coloring and bronzing of the said surface.

When a panel or other sunken or inserted figure is to be formed, I employ fixed and 55 movable grounds. The fixed grounds are employed to plaster to in the usual way; but the movable grounds are employed not only to plaster to as a boundary-line, but to preserve the bed, line, and surface for the casings, styles, and moldings, and to preserve the places for any desired figure, as illustrated by the block shown in Fig. 3 and the 60 groove and exposed lath shown in Fig. 4. In such case the ground or pattern is attached 65 to the lath and the plastering done all around it, and it is then removed and the required finish put into the space so left.

When a raised figure of large proportion is to be constructed, then a wire-gauze or other 70 suitable frame-work is employed as a foundation for the plastic work.

When concreted pebble surfaces require some special or a heavier grade in surface treatment, the first coat or scratch-coat is allowed to sufficiently dry to cause more absorption, when the second cement hair-mortar 75 coat is applied.

In all cases in the foregoing specification where "cement" is mentioned, plaster-of-paris 80 or other-like material may be used. I therefore do not confine myself to the use of "cement."

Having thus described my invention, what I claim, and desire to secure by Letters Patent, is--

The herein-described method of ornamenting walls and ceilings, which consists in applying a plastic coat thereto, and while said coat is wet dashing or hurling forcibly into 90 it gravel, cement, plaster-of-paris, or the like.

THEOPHILUS TUCKER.
